UNITED STATES PATENT OFFICE.

THOMAS C. VINSON, OF GUTHRIE, OKLAHOMA, ASSIGNOR OF ONE-FOURTH TO AMOS A. EWING AND ONE-FOURTH TO WALTER T. WARREN, BOTH OF GUTHRIE, OKLAHOMA.

COMBINED RAZOR HONE AND STROP.

1,242,746.

Specification of Letters Patent.

Patented Oct. 9, 1917.

Application filed October 7, 1916. Serial No. 124,313.

To all whom it may concern:

Be it known that I, THOMAS C. VINSON, a citizen of the United States, residing at Guthrie, in the county of Logan and State of Oklahoma, have invented certain new and useful Improvements in Combined Razor Hones and Strops; and I do hereby declare the following to be a full, clear, and exact description of the invention, such as 10 will enable others skilled in the art to which it appertains to make and use the same.

This invention relates to combined razor hones and strops, and one of the principal objects of the invention is to provide means 15 for supporting a hone and connecting a strop to the frame of the hone so that the strop or the hone can be used independently whenever desired.

Another object of the invention is to provide a hone having supporting devices at the ends thereof and said supporting devices being connected at one end to a hook or swivel and at the opposite end a strop or strops being connected thereto, so that a 25 razor can be honed or stropped at will, and means being provided whereby the strop may be removed from the hone whenever desired and replaced by others.

These and other objects may be attained 30 by means of the construction illustrated in the accompanying drawing, in which,

Figure 1 is a perspective view of a combined hone and strop, made in accordance with this invention.

Fig. 2 is an edge view of the supporting 35 yoke or frame at the upper end of the hone,

Fig. 3 is a front view of the same,

Fig. 4 is a front view of a portion of the hone and the yoke connected thereto for 40 supporting the strops,

Fig. 5 is an edge view of the same, and

Fig. 6 is a view in elevation of a slightly modified form of the yoke and manner of connecting the strops to the hone.

45 Referring to the drawing, the numeral 1 designates a hone of any suitable character or type, and connected to one end of the hone is a metal yoke or support 2 having a swivel 3 connected centrally thereto and 50 adapted to engage a hook 4 so that the hone may be reversed if desired. The yoke has pivotally connected thereto, on the inner sides of the arms 5, bars 6, which bars are pivoted as at 7 to the arms 5 and the inner

sides of the arms 5 are provided adjacent 55 their ends with hemispherical recesses or depressions. The bars 6 are provided with apertures which align with the recesses or depressions in the arms 5. The bars 6 having 60 extended through their apertures pins 8. The pins 8 extend through the apertures of the bars 6 into the holes of the side of the hone. The outer ends of the pins 8 are provided with heads, which are adapted to seat in the hemispherical recesses or 65 depressions formed in the inner sides of the arms 5 and thus prevent removal and at the same time hold the hone in alignment with the yoke at right angles thereto.

The outer end of the hone is also provided 70 with a similar yoke 9 having arms 10 and the bars 11 pivoted at 12 on the inside of said arms. The arms 10 are provided with recesses in alignment with the heads of the pins 14, said recesses 13 adapted to prevent the pins from withdrawal and also to hold the hone and yoke 9 in alignment.

75 The strops 15 are provided with a clamp 16, said clamp comprising two members connected to the yoke 9 and provided with 80 oppositely disposed key hole slots 17 to receive a double headed rivet or button 18 secured to the strops 15 and detachably connected to said clamp 16 by moving the head into coincidence with the larger portion of 85 the key hole slot.

As shown in Fig. 6, the yoke 19 is formed 90 of wire and is secured by headed fastenings 20 to the hone and a swivel 21 is connected to a loop 20^a in the yoke. At the opposite 90 end of the hone is a metal yoke 22 secured to the hone by means of fastenings 23, and the strops 24 are connected to a clamp 25 by means of a bolt 26 and thumb nut 27.

From the foregoing description, it will 95 be obvious that the combined hone and strop of this character, can be used to advantage to either hone or strop of the razor and it can be readily used whenever desired and the strop may be disconnected from the hone 100 or the hone disconnected from the strop so as to permit the ready intentional removal of the hone and substitution of another, and prevent accidental removal and it can be further seen that when strop is disconnected 105 from the hone it may be connected to any other suitable support, such as a nail or the like and used independent of the hone. It

will also be obvious that the strop can be used either with improved hone or separately as described.

Various changes may be made in the details of construction without departing from the spirit and scope of the invention as defined in the claims.

What is claimed is:—

1. A razor hone comprising a hone, a yoke removably connected to each end of said hone, bars pivoted to said yoke on the inner sides thereof, pins extending through the bars and adapted to engage in the opposite side edges of the hone, one of said yokes adapted to have removably secured thereto a strop.

2. A razor hone of the character described comprising a hone, a yoke pivotally connected to each end of the hone, one of said yokes provided with a swivel, bars connected to the arms of the yokes, pins extending through the bars and into the hone, said yokes provided with recesses adapted to engage the heads of said pins to hold the hone within the yokes, and parallel therewith, and the yoke remote from the yoke carry-

ing the swivel adapted to have a razor strop connected thereto.

3. A razor hone of the character set forth comprising a hone having holes on its opposite longitudinal sides near the opposite ends thereof, a pair of substantially U-shaped yokes, bars pivotally connected to the inner sides of the yokes, pins extending through the free ends of the bars and embedded in the holes in the sides of the hone to hold the same parallel with relation to the yokes, the arms of the yoke provided on their inner sides adjacent their ends with recesses adapted to receive the heads of the pins for holding the hone against accidental removal from the yokes, and a swivel connected to the web of one of said yokes, and the other of the said yokes adapted to removably support a razor strop.

In testimony whereof I affix my signature in presence of two witnesses.

THOMAS C. VINSON.
